HYDRAULIC PROPULSION OF SHIPS, BOATS,
AND OTHER FLOATING STRUCTURES

Witold Diamand, Lwow, Poland

Application March 6, 1939, Serial No. 259,963
In Great Britain May 5, 1937

14 Claims. (Cl. 115—13)

This invention relates to an improved hydraulic propelling mechanism for ships, boats and the like floating structures (hereinafter referred to collectively as boats) of the well known type acting through a water piston in which means the working delivery pipe is filled from an inlet conduit or pipe with water, which after the closing of the delivery pipe from the inlet pipe is accelerated (in the direction opposite to that of the boat's movement) by the expansion of gas which may be a combustible gas mixture or the like introduced into the delivery pipe through valve means.

The invention has for its object improvements upon the previously proposed mechanisms of this type, particularly in relation to the constancy of the speed of the water in the intake pipe. Another object is to provide means for cushioning the shock of the expansion of working gas in the delivery pipe.

The new propelling device according to the invention may be mounted within the hull of the boat with the water-inlet member and the outlet of the expansion tubes communicating with the outside water. It may also be constructed as a separate self-contained structure mounted within a special hull or casing and attached to the boat in any suitable way and at any suitable point.

According to this invention hydraulic propulsion means of the said type include an intake pipe associated with a plurality of delivery pipes and a rotary device which connects the intake pipe successively with the delivery pipes which are circularly arranged in relation thereto.

By this means a stream of nearly constant speed relatively to the body of the boat can be maintained in the inlet pipe.

Preferably shock absorbing mechanism is provided which takes the excess of pressure caused by the expansion of the working gas.

According to a further feature of the invention the delivery pipes may be provided over that portion of their length within which gas expansion takes place with a narrowed or restricted cross-section in order that the speed of the water flowing through may exceed that of the boat itself. This special arrangement has been found of particular usefulness in boats of small speeds, it permits higher initial pressures and the use of a more compact propulsion mechanism.

For shallow-going watercraft the hydraulic gear according to the invention is preferably so constructed that the depth of immersion of the outlet ends of the expansion tubes may be varied

during the travel of the boat. For this purpose the rear portion of the propelling mechanism may be turnable through a small angle about a horizontal axis. In these cases too the expanded gas preferably leaves the delivery tubes through their walls rather than at their ends. For this purpose small slits may be made in the walls of the delivery pipe the slits being cut on the top side of the delivery pipe at an angle to the axis thereof so that on the interior of the pipe the front edge of the slit, thus nearer the inflow end of the pipe, presents an acute angle with a sharp edge to the water and gas flowing therethrough, but on the exterior of the pipe the front edge of the slit presents an obtuse angle to the water flowing thereover, the slit therefore running backward from the inside to the outside of the pipe. Other similar slits may be arranged the opposite way round to take in water to replace the loss of volume due to the escaping gas. Experiment has shown, that by means of such slits the gas, escaping through the slits, can be separated in suitable circumstances from the water, and the decrease in volume may be made up in that part of the tube by supplying fresh water through the other slits which may be similarly constructed as the above described.

The inflow end of the common inlet pipe is preferably arranged about the middle of the boat's length.

A still further feature of the invention consists in the arrangement of a rotating valve disc controlling the water inlet to the delivery pipes by controlling the mouth thereof, cutting the same off the common water inlet tube during a period of time within which the compressed gas enters the delivery pipes (where it may be ignited), and subsequently expands, and providing a controlled valve mechanism introducing the compressed gas into the delivery pipes in the required quantities or portions and being preferably so constructed as to permit the use of comminuted fuel, for example, coal dust.

According to a further feature of the invention the boat propelling mechanism is provided at the inlet ends of the delivery pipes, with a quickly closing valve disc or plate, so arranged and actuated as to permit an accelerated closure of the delivery pipes and thus prevent disturbances at the inlet side thereof. This additional controlling element is preferably mounted upon the aforementioned rotating valve disc, so as to be positively actuated while rotating therewith.

The delivery pipes are preferably so curved, that the water passing through them will be sub-

jected to a centrifugal action in a direction opposite to gravity. This helps the formation of a water surface substantially normal to the direction of the water flow and adapted to act as a 5 piston surface.

All the amounts of compressed gas used are produced outside the operating cylinders and admitted to them while already being in their compressed condition.

- 10 The compressed air needed for combustion inside the delivery pipes or any kind of gas under pressure after being compressed in a separate compressor, may be heated up to the required temperature in a superheater of any suitable kind 15 16 by the heat quantities delivered, e. g. by exhaust gases of the internal combustion engine driving the aforementioned compressor.

In the particular case of a propelling mechanism using comminuted solid fuel, for example, 20 pulverised coal, the compressed air during the admission thereof into the delivery pipe passes over coal powder, carrying with it into the delivery pipe a quantity sufficient for one combustive operation, the air speed being so adjusted 25 that the coal powder will be distributed in and uniformly mixed with the compressed air admitted.

The air-fuel mixture under pressure introduced into the delivery pipe produces within the admission end thereof a water-free space so that the fuel carried along cannot pass into the water body so as to escape ignition. This action of keeping the fuel separate from the water body can be improved, according to a further feature 30 35 of the invention by the opening stroke of the mixture admitting valve being effected in two successive steps or stages. During the first stage the compressed air is kept off the fuel, so that compressed air alone will enter the operating cylinder. 40 Only when the second stage is reached will the compressed air pass over the powdered fuel so as to mix the same uniformly with the air and to inject it into the cylinder.

According to a still further feature of the invention the improved hydraulic propelling mechanism is associated with a pneumatic shock absorbing contrivance, by which the irregularities of the propelling force arising from the variable pressure in the delivery pipe, can be smoothed 45 50 out. This contrivance substantially consists of a part of the mechanism on which the gas pressure acts immediately to cause it to make in the direction of the boat's motion a slight reciprocating lengthwise movement. So for example a 55 pneumatic compensating contrivance may be employed in which the pressure of the expanding or burning gas acting upon such moveable part of the mechanism causes the displacement of a piston which reciprocates against the reaction 60 of the gas compressed in a compressed gas reservoir. This reciprocation induces a periodical change of the volume of the compressed gas reservoir. If therefore the volume of the reservoir is sufficient any small amount of the irregularity or variability of the boat's propulsive 65 force may be damped out.

Further features of the invention will be apparent from the subsequent description of the accompanying drawings illustrating more or less diagrammatically some embodiments of the invention.

In the said drawings:

Figure 1 is a partial longitudinal section.

Figure 2 is a cross section.

Figure 3 is a side view.

Figure 4 is a section through Figure 3.

Figure 5 is a section of a hydraulic device controlling the gas inlet valve.

Figure 6 is a cross section of the valve in the fully closed position.

Figure 7 is a cross section of the valve in the fully opened position.

Figure 8 is a longitudinal section of a pneumatic shock absorbing contrivance.

Figure 9 is a section through a delivery pipe 10 showing slits for the discharge of the expanding gases therethrough.

In the drawings the reference numeral 1 designates a main water inlet pipe through which a co-axial pipe 3 extends and to which is joined an 15 outer tubular extension 2. The outside water in which the boat floats thus may pass continuously through the annular space formed by the members 1, 2 and 3 respectively. At its rearward end the water inlet space is closed by a 20 disc 4 having an aperture 5 of the shape of a ring sector and being continuously rotated in the direction of the arrow (Fig. 2). On a circle concentric with the aperture 5 the centres of the substantially circular ends of a plurality of, for 25 example four, delivery pipes 6 are arranged upon which disc 4 rotates with a liquid tight contact. The disc 4 is actuated by a central shaft 7 and a suitable actuating mechanism, for instance a worm gear as indicated at 8 is indicated in the 30 drawings. The mouths of the pipes 6 are provided with lateral extensions, as indicated at 9 in the drawings. The pipes 6 are preferably of greater diameter at their outlet or discharge ends than at their inlet ends and extend lengthwise 35 substantially in the shape of a prolonged flattened S so that the water passing through the first bend which is bent downward will be subject to a centrifugal action counteracting gravitation, which tends to ensure that the water surface in the pipes 6 will be substantially normal 40 to the direction of the water flow, and thus causes a diminution of the surface of the gas space.

The disc 4 is located within a casing 10, the 45 edge 11 of the disc aperture 5 controlling the beginning of the water inflow from the main water inlet 1 into the delivery pipes. In order to accelerate the closure of the water inflow the disc 4 is provided adjacent the other end of 50 aperture 5 with a control flap 13 having a small inertia moment and being pivoted on a pin 14. This flap is adapted to shut the mouths or inlet ends of the delivery pipes off from the water inlet, as soon as the edge 12 of the lattice 15 has 55 advanced beyond the mouths of the delivery pipes and passed thereover. It is constructed of thin sheet metal and is supported against the gas pressure by a fixed sheet metal lattice 15. That lattice will be preferably situated in such a 60 position, as to oppose to the water stream, flowing therethrough after the reopening or before the closure of the flap, only a smallest possible resistance. The metal sheets forming the lattice may be thus placed approximately in the stream 65 line direction. The movements of the flap 13 are controlled by an actuating mechanism of which the cam 22 arranged on the inside of casing 10 and an oil pump 24 are shown in the drawing.

Within pipe 3 a pipe 25 is mounted, through which a gas under pressure, received from a suitable source, for example compressed air is fed to the delivery pipe. Pipe 25 rotates continuously in unison with disc 4, the space between it 70 75

and pipe 3 being filled with a suitable heat insulating material.

Disc 4 is intermediate its control edges provided with the inlet aperture for an expansible gas, for example a combustible gas mixture. This inlet aperture communicates with the backward end of the pipe 25 by a conduit not illustrated in the drawings and is controlled by a valve mechanism 26.

10 The cycle of operations is as follows: The disc 4 rotates in the direction of the arrow shown in Figure 2. Water flows into the pipes 6 from the time that the edge 11 of the disc aperture 5 has passed over them until the edge 12 of the lattice 15 has also passed over them. At this moment the control flap 13 closes the opening of the pipe 6 by a rapid movement, thus avoiding cavitation in the pipe which might occur if the closure was a slow one. The valve body 26 has meanwhile 20 come in front of the mouth of the delivery pipe. The compressed gas is injected into the mouth of the pipe is ignited and expands giving the working stroke. The mouth meanwhile of the pipe remains closed from water until the edge 11 of 25 the disc opening 5 again opens it.

One of the various possible means of operating the compressed gas valve is apparent from Figure 5. The valve stem is terminated by a plunger 33 which moves in a sleeve 34 connected with 30 an oil pump 35 by means of a pipe 36 which is full of oil. In the casing 10 of the disc 4 is mounted a concentric inner cam 27 on which a roller 28 rolls and controls the valve in question. The cam lug 29 will move the roller when it passes 35 over it and thereby also move the piston 31 downward, so that it expels the oil into the sleeve 34 and causes a movement of the plunger 33 and so opens the valve against the force of a spring 38 and of the gas pressure acting on the piston 40, which holds the roller against cam 27. The power output of the propelling mechanism will be controlled by effecting a change of the opening interval of the valve 26. A contrivance may be thus provided which brings this about by the 45 opening of an admission valve 40 (or of an over-flow valve) of the above oil pump. The circular cam, which controls that admission valve may be constructed so that it may be moved rotationally through a small angle in order to change 50 the opening moment of the admission valve or over-flow valve of the oil pump, and so to accelerate or retard the moment at which the valve 26 closes, and so to control the power output.

The disc 4 is further provided with suitable 55 gas igniting means not shown which at the proper moment of time cause the ignition of the combustible mixture admitted to pipes 6.

In the drawings a preferred embodiment of compressed air and fuel admission valve, adapted 60 to be incorporated with an internal combustion engine according to the invention, is shown diagrammatically. The reference numeral 41 designates the inlet opening controlled by the valve 42, the conical valve seat 43, a member 65 upon which the valve is mounted and having a front face 44 adapted to contact with the outer face of an expansion tube or cylinder, which is not illustrated in the drawings. The valve cone 45 located at a small distance behind the front 44 if the valve is closed, is attached to a discharge piston 46 by means of a valve stem comprising 70 a section 47 having a relatively large diameter and a section 48 of smaller diameter. The admission of the compressed air takes place through 75 apertures 49 which are in a continuous or in a

controlled communication with a suitable source of compressed air. The coal dust or powder is admitted through a passage 50 leading into a hollow sleeve 51. The outer end of sleeve 51 is closed by stem portion 47, if the valve is in 5 its closed position. When the valve opens stem portion 47 completely moves out from sleeve 51 so that compressed air may flow therethrough the valve operating as an injector and the compressed air carrying fuel with it and intimately 10 intermixing itself therewith. The quantity of fuel carried along depends upon the duration of the valve opening. If the same varies the quantities of compressed air and of fuel admitted to the expansion tubes are simultaneously varied. 15 The mechanical means for operating valve stem 47, 48 are not illustrated in the drawing and may be of any suitable kind.

As shown from the drawing the valve cone 45 has to travel a distance a , before the feed of fuel 20 from sleeve 51 can begin, the valve thus at each valve operation admits at first compressed air only and after the travel a has been effected compressed air and fuel are admitted.

The pulverised coal can be fed to the mixture 25 valve for example in the following manner. Inside the hollow shaft 7 might be mounted centrally a worm, by which the coal powder can be drawn into a space formed on the right side of the disc 4. Afterwards the coal powder will be 30 taken along with a small quantity of compressed air. This could be effected for example by an injector device supplied with compressed air from a small branch of the inlet air pipe located at a small distance from the place of the mixture inlet 35 valve to which the coal powder is to be supplied. The volume of the pipe leading from the injector into the mixture valve will be sufficiently great to provide the necessary mixture for one combustion operation the proportions of fuel to air 40 being such that combustion will be initiated in this chamber and will take place fully when it reaches the delivery pipe. The pulverised coal will reach the mixture valve with its temperature still raised, that is almost in a glowing state, and 45 will there become mixed with the quantity of heated and compressed air needed for the combustion process. The complete mixture present will be, after closing the valve, quickly ignited 50 inside the delivery pipe by suitable means of any kind; for example, an electric spark.

In a different embodiment of the ignition mechanism the coal powder mixed with the compressed air could be brought into the delivery pipe and be ignited therein. A small quantity of some 55 easily inflammable liquid fuel could be introduced into the mixture to facilitate ignition.

As shown in the drawing the outer tube 2 is rigidly connected with the control disc casing 10 and provided at 30 with a water tight joint 60 so that it may perform a slight reciprocating length-wise movement with respect to the main water inlet member 1. For permitting this movement a further anti-leakage packing is provided at 31 between pipe 3 and member 1, the whole 65 structure composed of disc 4, casing 10, tubes 6, shaft 7 and tubes 2 and 3 being mounted for reciprocating movement upon a suitable pneumatic, shock-absorbing mechanism 32, which absorbs the shocks caused by the propelling mechanism 70 and keeps them off the body of the boat.

Figure 8 shows one of the various possible embodiments of a double acting shock absorbing contrivance, adapted for compensation of the shocks caused by the boat propelling mechanism 75

which will act whether the movement of the boat is forward or backward. A fixed cylinder consists of two parts 52 and 53. Inside them a piston 54 rigid on a shaft 65 is secured to the propelling mechanism. On the other end of the shaft (which is well machined) a second piston 55 is freely mounted and reciprocates inside the cylinder 53. A ring 56 secured by means of a screw nut 57 forms a limitation of the stroke.

10 A second limitation consists of the shoulder 58 which is fixed to the body of the cylinder 53.

When the boat is travelling forward, and pressure exists in the cylinder 53 and the reservoir, piston 55 because of its greater area will be moved to the right, and will take with it piston 54 and the shaft 65 on which piston 54 is fixedly mounted and this movement will continue until piston 55 rests against the shoulder 58. In this position the hole 60 will be closed by sleeve 61.

20 The driving apparatus will then be in a position free to perform a further slight backward reciprocating movement and is balanced against such movement by the balance of pressure in the system formed by the cylinder and reservoir 25 on the one hand and the thrust between the driving apparatus and the boat on the other.

With an increase of such thrust the driving mechanism will move to the right. This will take with it shaft 65 and piston 54, which movement 30 will be resisted by the gas in the cylinder and reservoir.

If the average force of the thrust increases the shaft 65 and piston 54 will be displaced sufficiently to the right for hole 60 to pass beyond 35 the point 62. Gas will then flow into the system from the expansion chambers in the delivery pipes through hollow shaft 65 and orifice 60 until the thrust is again balanced, thereby creating a new datum pressure in the cylinder and reservoir.

40 If, on the other hand, the thrust diminishes to any extent, piston 54 will move to the left till holes 64 which are normally to the right of holes 63 come in register with the holes 63. This will allow pressure to escape until the balance is restored again creating a new datum pressure.

If the boat is moving backward and the thrust between the boat and the driving mechanism is in the opposite direction, the position of the parts will be with the piston 55 floating in the cylinder 53, hole 60 covered by the sleeve 61. The ring 56 prevents movement of piston 55 to the right. If the thrust of the mechanism increases there will be a pull to the left on the shaft 65 and on the two pistons 54 and 55. As piston 55 is of a greater effective area than piston 54, this will be resisted by the gas in the cylinder. The thrust of the mechanism is accordingly balanced against the pressure in the cylinder and reservoir.

60 Should, however, the average thrust of the system increase the parts will move into the position shown in the drawing, hole 60 will be uncovered by sleeve 61, gas will again flow into the cylinder from the hollow interior of shaft 65 and hole 60 returning the parts to their original position, restoring the balance and giving a new datum pressure.

If the average thrust falls piston 55 will be displaced further to the right by the pressure in the cylinder taking with it piston 54, the holes 64 will come into register with the holes 63 and allow pressure to escape until the correct datum pressure is again reached and the balance restored.

75 In Figure 9 the delivery pipe is shown at 66 the

direction of flow by the arrow 67 and the slits at 68.

What I claim is:

1. Means for hydraulic propulsion of boats through water which include an inlet pipe having the outer end open to the water outside the boat and an inner end inside the boat, a plurality of delivery pipes having outer ends open to the water outside the boat and inner ends inside the boat circularly arranged with reference to the inner end of the inlet pipe, means for introducing a gas into the delivery pipes and causing it to expand therein and a rotary device operating between the inner ends of the inlet and delivery pipes which connects the intake pipe 15 with the delivery pipes and successively closes off the delivery pipes from the intake pipes during the moment of the expansion of the gas in each delivery pipe.

2. Means for hydraulic propulsion of boats 20 which include an inlet pipe having the outer end open to the water outside the boat and an inner end inside the boat, a plurality of delivery pipes having outer ends open to the water outside the boat and inner ends inside the boat circularly arranged with reference to the inner end of the inlet pipe, means for introducing a gas into the delivery pipes and causing it to expand therein and a rotary device operating between the inner 25 ends of the inlet and delivery pipes and having an aperture of the shape of a ring sector adapted to come into register with the inner ends of the delivery pipes as the device rotates so that water will flow from the inlet pipe into the delivery pipes through such aperture and having a portion beyond such ring sector which is also adapted to come into register with the inner ends of the delivery pipes and close off from the inlet pipe in turn the ends of the delivery pipes during the expansion of the gas therein.

3. Means for hydraulic propulsion of boats 40 which include an inlet pipe having the outer end open to the water outside the boat and an inner end inside the boat, a plurality of delivery pipes having outer ends open to the water outside the boat and inner ends inside the boat circularly arranged with reference to the inner end of the inlet pipe, means for introducing a gas into the delivery pipes and causing it to expand therein and a rotary device operating between the inner 45 ends of the inlet and delivery pipes and having an aperture of the shape of a ring sector adapted to come into register with the inner ends of the delivery pipes as the device rotates so that water will flow from the inlet pipe into the delivery 50 pipes through such aperture and having a portion beyond such ring sector which is also adapted to come into register with the inner ends of the delivery pipes and close off from the inlet pipe in turn the ends of the delivery pipes during the expansion of the gas therein, said closing portion of the rotary device having a flap valve which is caused to be swung across the inner end of the delivery pipe with which it comes into register so as rapidly to close off the same from the inlet 55 pipe and a metal lattice which supports the flap valve against the pressure of expanding gas in the delivery pipe.

4. Means for hydraulic propulsion of boats 70 which include an inlet pipe having the outer end open to the water outside the boat and an inner end inside the boat, a plurality of delivery pipes having outer ends open to the water outside the boat and inner ends inside the boat circularly arranged with reference to the inner end 75

of the inlet pipe, means for introducing a gas into the delivery pipes and causing it to expand therein and a rotary device operating between the inner ends of the inlet and delivery pipes and having an aperture of the shape of a ring sector adapted to come into register with the inner ends of the delivery pipes as the device rotates so that water will flow from the inlet pipe into the delivery pipes through such aperture and having a portion beyond such ring sector which is also adapted to come into register with the inner ends of the delivery pipes and close off from the inlet pipe in turn the ends of the delivery pipes during the expansion of the gas therein, said closing portion of the rotary device having a flap valve which is caused to be swung across the inner end of the delivery pipe with which it comes into register so as rapidly to close off the same from the inlet pipe and a metal lattice which supports the flap valve against the pressure of expanding gas in the delivery pipe, the said rotary device also containing an intake valve through which the gas is supplied in turn to the delivery pipes, which valve is also brought into register with the inner ends of the delivery pipes as the rotary device rotates.

5. Means for hydraulic propulsion of boats through water which include an inlet pipe having the outer end open to the water outside the boat and an inner end inside the boat, a plurality of delivery pipes having outer ends open to the water outside the boat and inner ends inside the boat circularly arranged with reference to the inner end of the inlet pipe, means for introducing a gas into the delivery pipes and causing it to expand therein and a rotary device operating between the inner ends of the inlet and delivery pipes which connects the intake pipe with the delivery pipes and successively closes off the delivery pipes from the intake pipes during the moment of the expansion of the gas in each delivery pipe, the delivery pipes being curved so as to produce a centrifugal action opposed to gravity on the water in that part of the pipe in which the expansion of the gas takes place.

45. 6. Means for hydraulic propulsion of boats which include an inlet pipe having the outer end open to the water outside the boat and an inner end inside the boat, a plurality of delivery pipes having outer ends open to the water outside the boat and inner ends inside the boat circularly arranged with reference to the inner end of the inlet pipe, means for introducing a gas into the delivery pipes and causing it to expand therein and a rotary device operating between the inner ends of the inlet and delivery pipes and having an aperture of the shape of a ring sector adapted to come into register with the inner ends of the delivery pipes as the device rotates so that water will flow from the inlet pipe into the delivery pipes through such aperture and having a portion beyond such ring sector which is also adapted to come into register with the inner ends of the delivery pipes and close off from the inlet pipe in turn the ends of the delivery pipes during the expansion of the gas therein, said closing portion of the rotary device having a flap valve which is caused to be swung across the inner end of the delivery pipe with which it comes into register so as rapidly to close off the same from the inlet pipe and a metal lattice which supports the flap valve against the pressure of expanding gas in the delivery pipe, the said rotary device also containing an intake valve through which the gas is supplied in turn to the delivery pipes, which valve is also brought into register with the inner ends of the delivery pipes as the rotary device rotates.

the inner ends of the delivery pipes as the rotary device rotates, the expanded gases flowing out with the water from the ends of the delivery pipes.

7. Means for hydraulic propulsion of boats 5 which include an inlet pipe having the outer end open to the water outside the boat and an inner end inside the boat, a plurality of delivery pipes having outer ends open to the water outside the boat and inner ends inside the boat circularly 10 arranged with reference to the inner end of the inlet pipe, means for introducing a gas into the delivery pipes and causing it to expand therein and a rotary device operating between the inner ends of the inlet and delivery pipes and having 15 an aperture of the shape of a ring sector adapted to come into register with the inner ends of the delivery pipes as the device rotates so that water will flow from the inlet pipe into the delivery pipes through such aperture and having 20 a portion beyond such ring sector which is also adapted to come into register with the inner ends of the delivery pipes and close off from the inlet pipe in turn the ends of the delivery pipes during the expansion of the gas therein, said closing portion of the rotary device having a 25 flap valve which is caused to be swung across the inner end of the delivery pipe with which it comes into register so as rapidly to close off the same from the inlet pipe and a metal lattice 30 which supports the flap valve against the pressure of expanding gas in the delivery pipe, the said rotary device also containing an intake valve through which the gas is supplied in turn to the delivery pipes, which valve is also brought into register with the inner ends of the delivery 35 pipes as the rotary device rotates, the delivery pipes having slits on their upper surfaces serving as constantly open orifices for the expanded gases, the slit being shaped so that the angle in the inner wall of the pipe is on the inflow 40 side acute and on the outflow side obtuse.

8. Means for hydraulic propulsion of boats through water which include an inlet pipe having the outer end open to the water outside the boat and an inner end inside the boat, a plurality of delivery pipes having outer ends open to the water outside the boat and inner ends inside the boat circularly arranged with reference to the inner end of the inlet pipe, means for introducing a gas into the delivery pipes and causing it 45 to expand therein and a rotary device operating between the inner ends of the inlet and delivery pipes which connects the intake pipe with the delivery pipes and successively closes off the delivery pipes from the intake pipes during the moment of the expansion of the gas in each delivery pipe, the delivery pipes being mounted so that they are free to perform small reciprocating movements with reference to the boat which are resisted by a gas filled cylinder with a piston adapted to reciprocate therein and a gas 50 reservoir in communication with the cylinder.

9. Means for hydraulic propulsion of boats through water which include an inlet pipe having the outer end open to the water outside the boat and an inner end inside the boat, a plurality of delivery pipes having outer ends open to the water outside the boat and inner ends inside the boat circularly arranged with reference to the inner end of the inlet pipe, means for introducing a gas into the delivery pipes and causing it 65 to expand therein and a rotary device operating between the inner ends of the inlet and delivery pipes which connects the intake pipe with the delivery pipes and successively closes off the delivery pipes from the intake pipes during the 70 moment of the expansion of the gas in each delivery pipe, the delivery pipes being mounted so that they are free to perform small reciprocating movements with reference to the boat which are resisted by a gas filled cylinder with a piston adapted to reciprocate therein and a gas 75 reservoir in communication with the cylinder.

moment of the expansion of the gas in each delivery pipe, the delivery pipes being mounted so that they are free to perform small reciprocating movements with reference to the boat which are resisted by a damping device consisting of a cylinder, a piston in such cylinder connected to the delivery pipes, a reservoir in communication with such cylinder and valve means connecting the cylinder with the gases in the delivery pipes so that small movements of the delivery pipes following increase of pressure in the delivery pipes cause displacement of the piston which is resisted by the gas in the cylinder and greater movements cause the valve to be opened and further gas to be delivered to the cylinder so as to increase the resistance to displacement of the delivery pipes.

10. Means for hydraulic propulsion of boats as claimed in claim 9 the damping device also including another piston of greater area than 20 the said firstly mentioned piston which causes movement to be resisted also in the opposite direction to that in which it is resisted by displacement of first mentioned piston, and for the valve means which are opened to increase the 25 gas pressure on larger displacement.

11. Means for hydraulic propulsion of boats which include an inlet pipe having the outer end open to the water outside the boat and an inner end inside the boat, a plurality of delivery pipes 30 having outer ends open to the water outside the boat and inner ends inside the boat circularly arranged with reference to the inner end of the inlet pipe, means for introducing a gas into the delivery pipes and causing it to expand 35 therein and a rotary device operating between the inner ends of the inlet and delivery pipes and having an aperture of the shape of a ring sector adapted to come into register with the inner ends of the delivery pipes as the device rotates so that water will flow from the inlet pipe into the delivery pipes through such aperture and having a portion beyond such ring sector which is also adapted to come into register with the inner ends 40 of the delivery pipes and close off from the inlet pipe in turn the ends of the delivery pipes during the expansion of the gas therein, said closing portion of the rotary device having a flap valve which is caused to be swung across the inner end of the delivery pipe with which it comes into 45 register so as rapidly to close off the same from the inlet pipe and a metal lattice which supports the flap valve against the pressure of expanding gas in the delivery pipe, the said rotary device also containing an intake valve through which the gas is supplied in turn to the 50 delivery pipes, which valve is also brought into register with the inner ends of the delivery pipes as the rotary device rotates, with an oil pump, hydraulic means communicating the pump with the valve to cause the operation of the valve, a cam which operates a pump an overflow valve and a cam operating the overflow valve and controlling means by which the setting of the cams may be varied so as to control the amount of gas admitted by the valve.

12. Means for hydraulic propulsion of boats which include an inlet pipe having the outer end open to the water outside the boat and an inner end inside the boat, a plurality of delivery 60 pipes having outer ends open to the water outside the boat and inner ends inside the boat circularly arranged with reference to the inner end of the inlet pipe, means for introducing a gas into the delivery pipes and causing it to expand therein and a rotary device operating be-

tween the inner ends of the inlet and delivery pipes and having an aperture of the shape of a ring sector adapted to come into register with the inner ends of the delivery pipes as the device rotates so that water will flow from the inlet pipe into the delivery pipes through such aperture and having a portion beyond such ring sector which is also adapted to come into register with the inner ends of the delivery pipes and close off the inlet pipe in turn the ends of the delivery pipes during the expansion of the gas therein, said closing portion of the rotary device having a flap valve which is caused to be swung across the inner end of the delivery pipe with which it comes into register so as rapidly to close off the same from the inlet pipe and a metal lattice which supports the flap valve against the pressure of expanding gas in the delivery pipe, the said rotary device also containing an intake valve through which the gas is supplied in turn to the delivery pipes, which valve is also brought into register with the inner ends of the delivery pipes as the rotary device rotates, with an oil pump, hydraulic means communicating the pump with the valve to cause the operation of the valve, a cam which operates a pump an admission valve and a cam operating the admission valve, and controlling means by which the setting of the cams may be varied so as to control the amount of gas admitted by the valve.

13. Means for hydraulic propulsion of boats which include an inlet pipe having the outer end open to the water outside the boat and an inner end inside the boat, a plurality of delivery pipes 35 having outer ends open to the water outside the boat and inner ends inside the boat circularly arranged with reference to the inner end of the inlet pipe, means for introducing a gas into the delivery pipes and causing it to expand there- 40 in and a rotary device operating between the inner ends of the inlet and delivery pipes and having an aperture of the shape of a ring sector adapted to come into register with the inner ends of the delivery pipes as the device rotates 45 so that water will flow from the inlet pipe into the delivery pipes through such aperture and having a portion beyond such ring sector which is also adapted to come into register with the inner ends of the delivery pipes and close off from the 50 inlet pipe in turn the ends of the delivery pipes during the expansion of the gas therein, said closing portion of the rotary device having a flap valve which is caused to be swung across the inner end of the delivery pipe with which it comes into 55 register so as rapidly to close off the same from the inlet pipe and a metal lattice which supports the flap valve against the pressure of expanding gas in the delivery pipe, the said rotary device also containing an intake valve through which the gas is supplied in turn to the 60 delivery pipes, which valve is also brought into register with the inner ends of the delivery pipes as the rotary device rotates, a supply of air to said valve, means for putting said air under pressure, a supply of comminuted fuel to said valve delivering said fuel into the air stream so that it passes from said valve into the delivery pipes mixed with air.

14. Means for hydraulic propulsion of boats 70 which include an inlet pipe having the outer end open to the water outside the boat and an inner end inside the boat, a plurality of delivery pipes having outer ends open to the water outside the boat and inner ends inside the boat circularly 75

arranged with reference to the inner end of the inlet pipe, means for introducing a gas into the delivery pipes and causing it to expand therein and a rotary device operating between the inner 5 ends of the inlet and delivery pipes and having an aperture of the shape of a ring sector adapted to come into register with the inner ends of the delivery pipes as the device rotates so that water will flow from the inlet pipe into the delivery 10 pipes through such aperture and having a portion beyond such ring sector which is also adapted to come into register with the inner ends of the delivery pipes and close off from the inlet pipe in turn the ends of the delivery pipes during 15 the expansion of the gas therein, said closing portion of the rotary device having a flap valve

which is caused to be swung across the inner end of the delivery pipe with which it comes into register so as rapidly to close off the same from the inlet pipe and a metal lattice which supports the flap valve against the pressure of expanding 5 gas in the delivery pipe, the said rotary device also containing an intake valve through which the gas is supplied in turn to the delivery pipes, which valve is also brought into register with the inner ends of the delivery pipes as the rotary device rotates, said supply of fuel being so arranged that on opening the valve air will 10 pass at first into the delivery pipe and thereafter air mixed with fuel.

WITOLD DIAMAND. 15
